(57) **CLAIM**

The ornamental design of a coaxial connector, as shown and described.

DESCRIPTION

This application claims the benefit of U.S. patent application having Ser. No. 13/284,553 and titled Coaxial Connector filed on the same day, claims the benefit of U.S. patent application having Ser. No. 13/284,577 and titled Coaxial Connector filed on the same day, and claims the benefit of U.S. Design patent application having Ser. No. 29/405,151 and titled Coaxial Connector filed on the same day, the subject matter of each of which are herein incorporated by reference in their entirety. FIG. 1 is a front perspective view of a coaxial connector showing our new design.

FIG. 2 is a back perspective view of the coaxial connector shown in FIG. 1.

FIG. 3 is a side view of the coaxial connector shown in FIG. 1.

FIG. 4 is a front view of the coaxial connector shown in FIG. 1; and,

FIG. 5 is a back view of the coaxial connector shown in FIG. 1.
